IMPROVING COLOR OF LUBRICATING OILS AND WAXES

James Van Dyck Fear, Upper Providence, Pa., assignor to Sun Oil Company, Philadelphia, Pa., a corporation of New Jersey

No Drawing. Application December 30, 1955
Serial No. 556,424

5 Claims. (Cl. 208—27)

This invention relates to the improvement of color of hydrocarbon fractions and, more particularly, to improving the color of oils and waxes derived from the bottoms fraction of a cracked gas oil, although the invention is also applicable to the treatment of other lubricating fractions.

It has been known for some time that a high V.I., highly stable lubricating oil boiling between about 500° F. and 1100° F. may be produced by fractionating the products of catalytic cracking of a virgin gas oil to recover a bottoms product boiling above 500° F., and then solvent extracting and dewaxing this product. The oil so produced is, however, too dark for ready customer acceptance, and the wax recovered in the dewaxing step is also off-color. It has therefore been necessary, in order to render both oil and wax salable, to redistill and/or treat them with clay or other adsorbent material. Such treatments, while effective to improve the color of the oil and wax to a point where they meet specifications, involve a not inconsiderable treating loss. In redistillation, from about 3 to 10 percent of the product treated is recovered as a highly colored bottoms valuable only as an ingredient of heavy fuel oil and a light clay treatment is generally necessary in order to recover products of acceptable color. Even higher losses are incurred in clay treating without redistillation due to adsorption of oil and wax constituents on the clay. Furthermore, uneconomically large quantities of clay must be used to effect a sufficient degree of decolorization.

It is an object of this invention to provide a process for treating off-color lubricating oils to improve the color, while permitting an almost quantitative recovery of the oil so treated.

It is a further object of the invention to provide a process for improving the color of the wax content of a cracked gas oil.

I have found that the foregoing objects may be attained by solvent extracting that fraction of a cracked gas oil boiling above about 500° F. to remove low V.I. components such as aromatics, then adding to the raffinate at least about 3 to 5 percent of a higher-boiling hydrocarbon fraction and distilling the mixture to recover overhead a fraction equal in volume to the raffinate content of the mixture. It has been found that by so proceeding, the major part of the color bodies will be left behind in the still bottoms, and the overhead fraction may be dewaxed to yield a light-colored lubricating oil which may be further processed to separate it into various fractions of different viscosities, as desired, and an improved color paraffin wax which may be made colorless by treatment with a small amount of clay. While the process of the present invention does not entirely eliminate clay treating, it does greatly reduce the color, and hence reduces the severity of any subsequent finishing treatment required. Alternatively, of course, instead of taking the decolorized raffinate over in one fraction,

side streams of varying viscosities may be taken off during the distillation from the high boiling oil. While I prefer to add only about 3 to 5 percent of the higher boiling fraction to the raffinate, there is no objection to adding more, since the end result will be the same. However, it is not necessary to add more than 5 percent, and the addition of larger amounts will increase the equipment cost and heat load necessary to process a given amount of raffinate.

10 In alternative forms of the present invention, the gas oil bottoms may be distilled from the heavy oil before solvent treatment, or the oil may be dewaxed prior to distillation. In the latter case, the oil and wax fractions would each be subjected to distillation from the heavy oil to effect color improvement of each fraction.

While any high boiling oil, such as bright stock, may be used as the higher boiling component of the mixture, I prefer to use a residual oil which has value only as a component of heavy fuel oil. The added color bodies 20 which this oil will pick up in the process will not adversely affect its value as a fuel oil, so that after use in the process, it may be sold for the same price as if it had not been so used. Thus, in the practice of my new process, there is no loss or degradation in value of any of the fractions charged to the process, and the oils and waxes are decolorized at a minimum cost, since the major portion of the heat required for distillation would be required in any event in the separation of the oil into fractions of differing viscosities.

30 In order that those skilled in the art may more fully appreciate the nature of my invention and the method for carrying it out, the following example is given:

EXAMPLE I

35 A wide-cut gas oil boiling between 500° F. and 1000° F. was catalytically cracked, and the products were fractionated to yield gasoline, light fuel oil and a bottoms product boiling over 500° F. The bottoms was then extracted with furfural to yield a waxy oil of lubricating viscosity. This oil had an O.D. color of 177, which is too dark to be commercially acceptable. Nineteen parts of this waxy oil were then mixed with one part of bright stock and the mixture was vacuum distilled until nineteen parts were taken overhead, equal to the volume of waxy oil in the mixture. Characteristics of the oil and bright stock before and after this distillation are shown in the following table:

Table I

	Components in Charge		Products	
	Waxy Oil	Bright Stock	95% Distillate	5% Bottoms
Boiling Range, ° F.:				
Init.	496	959	503	927
5%	606	1,001	591	963
10%	658	1,024	656	981
50%	776	—	770	—
90%	850	—	844	—
95%	867	—	861	—
B.P.	898	—	906	—
O.D. Color	177	299	18	3,461

65 As may be observed, a volume of oil was recovered equal to the waxy oil charged and having the same boiling range as the original oil. The major part of the color bodies, however, had been removed to yield an oil of acceptable color. This oil may be dewaxed by conventional methods to yield a high V.I., low pour point, lubricating fraction, and a scale wax which may be deoiled to make a fully refined wax in all respects of as good quality as may be obtained from the wax distillate

fraction of crude petroleum, whereas the wax obtained from the waxy oil without treatment in accordance with the present invention is excessively dark in color compared to wax from distillate fractions of crude petroleum. If the virgin gas oil charged to the cracking operation is of a type which does not contain any appreciable amounts of wax, such as the gas oil obtained from a so-called "grade A" crude, the dewaxing step may be omitted.

While, as stated above, in commercial practice a heavy residual fuel oil fraction would be the preferred heavy component of the mixture, bright stock was chosen for this example for the reason that a change in its color during the distillation is measurable, to show that the color bodies in the oil charge are retained in the heavy fraction during distillation. If a black heavy oil had been used, it would have been impossible to accurately detect any color change.

While the foregoing description has been limited, for the purposes of example, to the treatment of lubricating oils derived from a cracked gas oil, the invention is also applicable to the treatment of highly colored lubricating oils derived from any source, provided only that their end boiling points are low enough so that a higher boiling hydrocarbon may be mixed therewith, and further provided that the color bodies in the oil are high-boiling enough to remain behind in the distillation bottoms. Whether or not the color bodies are of such a nature may easily be determined by conducting a test in accordance with the procedure outlined above. As an example of other oils which may be upgraded color-wise by my invention, oils which have picked up colored contaminants in use may be mentioned. Accordingly, the appended claims should be broadly construed as applying to the processing of any lubricating oils which may be benefited by the application of the invention thereto.

I claim:

1. A process for producing lubricating oils which comprises catalytically cracking a gas oil boiling between about 500° F. and 1100° F., segregating from the cracked products the fraction boiling above 500° F., solvent extracting said fraction to obtain an extract rich in low

V.I. components and a raffinate rich in high V.I. components, admixing with said raffinate at least 3% of its volume of a hydrocarbon fraction essentially all of which boils above the end boiling point of the raffinate, fractionally distilling the mixture, and recovering an overhead product approximately equal in volume to the raffinate, said product being lighter in color than the raffinate.

2. The process according to claim 1, including the step of dewaxing the said overhead product.

3. A process for producing waxes which comprises catalytically cracking a gas oil boiling between about 500° F. and 1100° F., segregating a wax-containing fraction from the cracked products, admixing with said fraction at least 3% of its volume of a hydrocarbon fraction essentially all of which boils above the end point of the wax-containing fraction, fractionally distilling the mixture, recovering an overhead product approximately equal in volume to the wax-containing fraction, and segregating wax from the overhead product.

4. A process for producing lubricating oils which includes the steps of catalytically cracking a gas oil boiling between about 500° F. and 1100° F., segregating from the cracked products a heavy fraction boiling above 500° F., admixing with said fraction at least 3% of its volume of a hydrocarbon fraction essentially all which boils above the end boiling point of the heavy cracked fraction, fractionally distilling the mixture, and recovering an overhead product approximately equal in volume to the heavy cracked fraction.

5. The process according to claim 4 including the step of solvent extracting the overhead product, and recovering as raffinate an oil of improved V.I.
